CHEST OR THE LIKE

Ernest Herrmann, Hillsdale, N. J., assignor to Heywood-Wakefield Company, Gardner, Mass., a corporation of Massachusetts

Application December 14, 1954, Serial No. 33,559

Term of patent 7 years

(Cl. D33—19)

FIG. 1.

Fig. 1 is a front perspective view of a chest showing my new design;

Fig. 2 is an enlarged fragmentary view along the line 2-2 of Fig. 1, partly in section and partly in perspective;

Fig. 3 is an enlarged fragmentary cross-section on the line 3-3 of Fig. 1; and

Fig. 4 is an enlarged perspective view of one of the handle elements, the stippling on said handle indicating contrast.

I claim:

The ornamental design for a chest or the like, substantially as shown and described.
